TERRAZZO STRIP

Joseph Laneri, Brooklyn, N. Y.

Application October 3, 1934, Serial No. 746,640

7 Claims. (Cl. 94—17)

This invention relates to terrazzo strips.

An object of my invention is to provide a terrazzo strip having highly improved interlocking means for retaining the strip embedded within the terrazzo floor.

A further object of this invention is to provide a heavy top terrazzo strip of the character described, having improved means for attaching the heavy top edging member without the use of rivets or other fastening means.

A still further object of this invention is to provide a neat, compact and rugged terrazzo strip of the character described, which shall be comparatively inexpensive to manufacture and practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a top plan view of a portion of terrazzo flooring, provided with dividing strips embodying the invention, with parts in cross-section;

Fig. 2 is a side elevational view of a terrazzo strip embodying the invention embedded in flooring;

Fig. 3 is a cross-sectional view taken on line 3—3 of Fig. 2;

Fig. 4 is a cross-sectional view taken on line 4—4 of Fig. 2;

Fig. 5 is a transverse, cross-sectional view, similar to Fig. 3, but disclosing a heavy top terrazzo dividing strip embodying the invention;

Fig. 6 is a perspective view of the strip shown in Figs. 1, 2, 3 and 4; and

Fig. 7 is a perspective view of the strip shown in Fig. 5.

Referring now in detail to the drawing, 10 designates a portion of terrazzo flooring and comprises a base layer 11 and an upper terrazzo layer 12, in which there are embedded a plurality of dividing or separating members 14 embodying the invention. The members 14 are disposed in vertical planes and may be arranged in any suitable pattern, as is well known in the art, the upper edges of said members being flush with the surface of layer 12.

The member 14 comprises an elongated, flat, relatively thin strip, preferably made of brass,

bronze or the like material. The same is provided with a plurality of openings 15, preferably alternately oppositely disposed. The shape of the openings 15 is preferably of a truncated triangle. It will be noted that one opening 15 has side edges 16 inclined inwardly and downwardly, whereas the next adjacent opening 15 has side edges 16 inclined inwardly and upwardly.

At spaced intervals, the strips are provided with interlocking portions 17. Each portion 17 comprises a tab 18 cut from the material of the strip and bent to incline upwardly and outwardly from the plane of the strip 14. The tab 18 has likewise the shape of a truncated triangle and has upwardly and inwardly inclined side edges 19 and a top horizontal straight edge 20. Cut from the tab 18 is an inner tab 21, likewise having the shape of a truncated triangle and bent to incline to a greater degree than the tab 18. The tab 21 likewise has upwardly and inwardly inclined side edges 22 and a top horizontal edge 23. It will be noted that by cutting the tabs 18 and 21, openings 24 and 25, respectively, are formed in strips 14 and tab 18, to permit interconnection of the terrazzo layer on both sides 25 of the strip 14 through said openings. Preferably, one interlocking portion 17 projects to one side of the strip 14, whereas the next adjacent interlocking portion 17 projects to the opposite side of said strip, as shown in Fig. 6 of the drawing. 30

The terrazzo layer 12 on opposite sides of the strip 14 is also interconnected through the openings 15. In this manner the strip 14 is firmly embedded in the layer 12. The projecting tabs 18 and 21 serve to firmly hold the strip 14 within 35 the layer 12.

In Figs. 5 and 7 there is shown a terrazzo strip 27 of the heavy top type. The same comprises an elongated strip 30 made of substantially thin metal; for example, brass or bronze. Said strip 40 30 is provided with openings 15a and interlocking portions 17a similar to the openings 15 and portions 17 of the strip 14. Said strip, however, is provided adjacent the upper edge thereof with a portion 31 bent out of the plane of the strip, 45 but disposed parallel to the body of said strip and being connected thereto by the portion 32. Extending from the upper edge of the portion 31 are a plurality of spaced folded-over tabs 33 for the purpose hereinafter appearing.

Attached to the strip 30 is a heavy top edging member 35 of substantial T-shape cross-section, having a relatively thick upper portion 36 and a downwardly extending relatively thin flange 37, preferably of the same thickness as the strip 30. 55

The flange 31 is formed with spaced slots 38 receiving the tabs 33. Said flange 31, as shown in Fig. 5, is disposed in the plane of a strip 30 and contacts one surface of the portion 31 of said strip. The tabs 33 pass through the slots 38 and contact an opposite surface of the flange 31 for firmly attaching the member 35 to the strip 30.

It will be noted that the body of the strip 30 is substantially in a plane bisecting the top portion 36 of the member 35. The member 21 may be embedded within the terrazzo layer 12 with the top surface 40 of the portion 36 of said member 35 flush with the top surface of said layer. It will now be understood that the member 21 will be firmly embedded and interlocked within the terrazzo layer by the interlocking portions 17a and by reason of the terrazzo material passing through openings 15a. The use of the tabs 33 obviates the necessity for rivets, screws, or other fastening devices for attaching the member 35 to the strip 30.

In assembling the member 21, the tabs 33 are first bent at right angles to said strip 30. Said tabs may then be inserted through the slots 38 by a sidewise movement and bent downwardly for firmly clamping the flange 31 to the strip 30.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. A terrazzo strip having a tab cut from the material thereof and extending to one side thereof and being inclined upwardly, and a second tab cut from the material of the first tab and extending to one side of said first tab and being inclined upwardly and disposed at an angle to said strip and first tab.

2. A terrazzo strip having a tab cut from the material thereof and extending to one side thereof, and a second tab cut from a portion of the first tab wholly inwardly of the edges thereof, and extending at an angle to said first tab and strip.

3. A terrazzo strip having a tab cut from the material thereof and extending to one side thereof, said tab being inclined upwardly and being of truncated triangular shape having upwardly and inwardly inclined side edges and a top horizontal edge, a second tab cut from the material of the first tab and likewise being inclined upwardly, but at a different angle from the first tab.

4. A terrazzo strip having a tab cut from the material thereof and extending to one side thereof, said tab being inclined upwardly and being of truncated triangular shape having upwardly and inwardly inclined side edges and a top horizontal edge, a second tab cut from the material of the first tab and likewise being inclined upwardly, but at a different angle from said first tab, said second tab likewise being a truncated triangle in shape and having upwardly and inwardly inclined edges and a top horizontal edge.

5. A terrazzo strip comprising an elongated flat, relatively thin strip of metal having parallel side edges, a tab cut from the material thereof and extending to one side of the strip and being inclined upwardly, and a second tab cut from a portion of the first tab wholly spaced from the outer edge thereof and being inclined upwardly and disposed at an angle to said first tab and strip, and said strip being formed with a plurality of openings spaced from said tab.

6. A terrazzo strip having a tab cut from the material thereof extending to one side thereof and being inclined upwardly, said tab having a portion thereof cut therefrom and extending at an angle thereto and being inclined upwardly but at a different angle from said tab, and a second tab cut from the material of said strip and extending to the opposite side of said strip and inclined upwardly, said second tab having a portion cut therefrom and bent out of the plane thereof and being inclined upwardly but at a different angle from said second tab.

7. A terrazzo strip comprising an elongated flat, relatively thin strip of metal having parallel longitudinal edges, a tab cut from the material of said strip and bent to one side thereof, and a second tab cut from a portion of the first tab and being inclined to said first tab and strip, said first and second tabs being bent at the bases thereof on a substantially common line.

JOSEPH LANERI.
